FASTENING DEVICE

John Francis Golubies, Los Angeles, Calif.

Application March 10, 1950, Serial No. 148,949

2 Claims. (Cl. 24—221)

1

This invention relates to a fastening device adapted to hold pocket combs or other devices of the type which are formed of half-portions joined in hinged relationship so as to enable the one half-portion to be in juxtapositioned relationship with respect to the other half-portion, and the prime object of the invention is to provide a simple, sturdy and efficient construction adapted to hold the half-portions of the comb in either folded or extended position.

Other objects, features, and advantages of the invention may be observed from a study of the following detailed description, the drawing, and the subjoined claims.

In the drawing:

Figure 1 is a side-elevational view of the comb of this invention in folded position.

Figures 2 and 3 are side-elevational views of the combs elements forming the article shown in Figure 1.

Figure 4 is a sectional view taken along line 4—4, Figure 1, showing the manner in which the convexo-concave teeth of the comb elements lie in back-to-back relationship when folded, and showing the spheroidal pocket between the teeth when the comb is folded whereby an accessory may be accommodated therein.

Figures 5 and 6 are transverse sectional views of the sub-comb elements taken along lines 5—5 and 6—6 in Figures 2 and 3 showing construction related thereto.

Figure 7 is a side-elevational view of the slotted side of one sub-comb element of the combination, being representative of the sub-comb shown in Figure 3 and includes a nail file in elevational view lying within a recess therefor and adjacent the convexo-concave side of certain of the teeth thereof.

Figure 8 is a side-elevational view of the comb which is similar to Figure 1, but is modified therover in that the nail file is shown extended to functional use position.

Figure 9 is an end elevational view taken along line 9—9 in Figure 8 and is adapted to show separation of the half-portions or sub-combs of the assembly to release the nail file or other accessory from there-between.

Figure 10 is an elevational view of the comb in extended or functional use position; and,

Figures 11 and 12 respectively, are sectional and elevational views showing the device I employ to hold the sub-combs in functional position, that is, in either folded or in extended position.

The device 1 in the present disclosure comprises two half-portions or sub-combs 2 and 3

2

which are hingedly joined together by a fastening device 4 so as to enable the sub-combs to be folded upon themselves or extended as need be under a degree of resilient tension, as is best shown in Figures 1 and 10.

Each of the sub-combs are formed with a body 5 having flat and parallel faced ends 6 from which there extends a finger 7 having teeth 8 rooted therein. The teeth 8 are convexo-concave intermediately of their root with the fingers 7 and their free ends, so that when the comb is folded and the teeth thereof lie in juxtapositioned relationship, there exists a spheroidal clearance 9 therebetween, and in this connection it is to be noted that the sub-comb 3 is formed with a shallow, right angled recess 10 in its face 6, the utility of which, including the clearance area 9 will be subsequently pointed out.

Each of the body portions 5 are formed with flanges 11 extending substantially the length thereof and are so located and proportioned that when the comb is folded the teeth of the one sub-comb will lie within and under the flange upon the other of the sub-combs, see Figure 4.

It is to be noted that each of the sub-combs 2 and 3 is provided with a transverse bore 12 to receive the fastening device 4. Since the sub-combs swing around the axis of the bore 12, it is necessary in order to properly nest these parts that they be located with a degree of definition; accordingly, I locate the center of the bores 12 on the face portions 6 of the sub-combs by reference to a radius tangential to a plane coincidental with the free ends of the teeth 8 and extending through 90 degrees to tangency at 14 with a transverse plane coincidental with the related end of the sub-combs. The material between the points 13 and 14 is removed to form a uniform radial shoulder.

Beginning at point 14 the edges of the faces 6 are spheroidal and extend in an arc 15 to a point 15a which is coincidental with a transversely placed plane passing through the point of beginning of the radius afore-mentioned. From the point 15a and outwardly therefrom in a line coincidental with said last mentioned transverse plane, I form a shoulder 16, and inwardly and downwardly through the flanges 11 from point 15a, I form an arcuate cut-away 17 having the same degree of curvature as the arc 15 aforementioned.

The cut-away 16 in the one sub-comb is adapted to accommodate the spheroidal shoulder (arc) 15 of the other of the sub-combs, so that as they are swung around the axis of their hinged union,

the shoulders 16 are brought into abutting contact and form a self-imposed lock against further rotation, thereby holding the sub-combs in end alignment with respect to one another.

Reference has previously been made to the fact that the sub-combs 2 and 3 are hinged together by means of the fastening device indicated by the reference numeral 4.

In Figures 11 and 12 I show in detail the structure of the fastening device 4 which is shown as 10 comprising the tubular sleeves 18 and 19 which are slidably fitted together and are formed with one closed end upon each thereof in the nature of a button-like finger grip 20 and 21. The sleeve 19 is formed with diametrically opposed slots 22 to receive the lugs 23 of a cradle 24 which is freely movable within the bore 25 thereof. A spring 26 placed within the bore 25 is seated in the cradle 24 and is retained therein by means of lips 27 struck from the inner ends of the sleeve 19 and bent over the end coil of the spring 26.

The sleeve 18 is formed with diametrically opposed bayonet slots 28 to receive the free end of the lugs 23 in their extension through the sleeve 19, and which lugs bear upon the closed ends of the bayonet slots under expansive pressure exerted by spring 26 when in functional position.

It is to be noted that the slot 22 is of such length as will provide an amount of clearance 22a and 22b upon each side of the lugs as will accommodate positional self-adjustment of the cradle when the fastener is assembled and in functional use.

After the half-portions or sub-combs have been constructed as aforementioned, they are assembled by sliding the sleeve 18 through the bores 12, and then sliding the sleeve 19, with the spring 26 in its cradle 24, therein, that is, into the sleeve 18 with the bayonet slot 28 aligned to receive the free ends of the lugs 23. Inward and rotational pressure upon the sleeve assembly 19 will cause the lugs to travel the length of the slots 28 and upon release they will bear upon the closed ends 30 thereof as shown in Figure 12.

Since the spring is installed in the sleeve 19 under a predetermined degree of compression, it follows from the disclosure that it will exert pressure in one direction upon the cradle 24 and that this pressure is transferred through the lugs thereof to the sleeve 18, and in the opposite direction upon the lips 27 of the sleeve 19 within which it is confined, which pressure tends to force the sleeve 19 inwardly of the sleeve 18.

Thus it will be seen that the expansive pressure of the spring 27 is so directed as to cause the finger grips 20 and 21 to converge upon one another in proportion to the degree of initial compression of the spring, and the thickness of the material interposed between the finger grips 20 and 21, which in the present instance comprise the combined thickness of the sub-combs.

The fastening device is removed from its assembly by inward pressure upon the finger grips and counter-rotation thereof.

From the preceding description it will be apparent to all those familiar with the art that I have conceived a novel fastening device for a comb construction, a comb which when in extended form is adapted to any use to which a

common form of comb may be put, yet at the same time the comb in its several aspects is so constructed as to protect the teeth thereof when not in use, and that the fastening device generally indicated at 4 and more particularly illustrated in Figures 11 and 12 provides a novel and very efficient fastening means adapted to various uses other than that herein shown as an application thereof.

It is to be understood that the form of the invention herewith shown and described is to be taken or considered as being the preferred embodiment of the same and that various changes in the shape, size and arrangement of the parts 15 may be resorted to without departing from the spirit of the invention or the scope of the subjoined claims.

I claim:

1. A fastening device, a first sleeve and a second sleeve, said sleeves being in slidable telescopic union with one another and having a closed end in each thereof, said first sleeve being formed with bayonet slots beginning in the lip of the open end of said sleeve and being terminal inwardly thereof, said second sleeve being formed with slots in its sides intermediately of its ends, a cradle in said second sleeve having laterally disposed lugs adapted to extend through the slots therein and into said bayonet slots and in pressure contact with the closed end of said bayonet slots, and a spring seated in said cradle and confined therein against displacement.

2. In a fastening device utilizing a pair of telescoped tubular sleeves comprising a first sleeve and a second sleeve, said first tubular sleeve having an open end and a closed flanged end and being formed with arcuate slots extending through the lip of the open end to a terminus within the walls thereof, said second tubular sleeve having an open end and a closed flanged end and being formed with slots intermediate of the ends thereof, a cradle within said second sleeve, said cradle having radial lugs thereon so disposed as to extend through and radially from said second mentioned slots to within and upon the terminal ends of said arcuate slots in said first mentioned sleeve, a compressed extensible spring within said second sleeve having one end nested in said cradle and being held confined under pressure therein by inturned flanges on the lip on the open end of the second sleeve, said slotted sleeves, the cradle and spring being so constructed and arranged that upon assembly thereof said spring in its expansive pressure exerts an oppositely directed pressure upon said sleeves whereby they are caused to move convergingly of one another.

JOHN FRANCIS GOLUBICS.
